LOCK

Filed May 27, 1929

UNITED STATES PATENT OFFICE

PETER MARKOVICH, OF GIG HARBOR, WASHINGTON

LOCK

Application filed May 27, 1929. Serial No. 366,300.

This invention relates to locks, and more particularly to permutation locks of that character designed for use in connection with electrically controlled devices, or with bolt locks; the principal object of the invention being to provide a lock which may be released only by an exact setting of parts, as determined by adjustment of a pointer, or indicator, to a predetermined numeral on the lock dial and, if an attempt to open the lock is made without this exact setting, such as might be done by an unauthorized person, the mechanism is automatically set against any further trial, and can only be released by a person knowing a second predetermined numeral on the dial to which the indicator must be adjusted in order to permit re-setting.

Other objects of the invention reside in the details of construction and combination of the various parts and especially in the novel means provided for re-setting the lock after it has been tampered with by an unauthorized person.

In accomplishing these and other objects of the invention, I have provided the improved details of construction, the preferred forms of which are illustrated in the accompanying drawings, wherein—

Figure 1 is a face view of a lock embodying the present invention, a part of the front wall of the lock casing being broken away for better illustration.

Figure 2 is a cross sectional view of the lock, taken on line 2—2 in Figure 1.

Figure 3 is a side view and sectional detail, showing the lock parts during a re-setting operation.

Figure 4 is a sectional detail of the lock arm.

Figure 5 is a detail of a contact member of an electric circuit connected with and controlled by the lock.

Figure 6 is a sectional detail, showing the alternative use of a bolt in the lock instead of the circuit member.

Referring more in detail to the drawings—

The lock casing 1 is of cylindrical form and is closed by a back wall 2 and a front wall 3; the former, as herein shown, being integral with the casing and the latter being fitted

within and secured to the casing by a plurality of pins, or screws, 4. The front wall 3, preferably, is set back within the casing and has a beveled peripheral surface 5, serving as a dial surface on which a series of numerals are placed for reference in setting and releasing the lock. A glass panel 7 overlies the dial and end of the casing, and this is held in place by a flanged collar 8 that is fixed about the casing and serves as a means whereby it may be fixed to a supporting panel 9.

Mounted within the casing, coaxially thereof, is a shaft 10 which has a reduced inner end portion 10a fixed within an opening 11 in the base wall 2. This shaft extends outwardly through and beyond the wall 3 and the glass panel 7. A sleeve 12 is slideable lengthwise on the shaft 10 and has a knurled knob 13 at its outer end, by means of which it may be rotated, or pulled outwardly or pushed inwardly on the shaft. A bushing 15 encloses the outer portion of the sleeve 12 and is revolvably fixed in an opening in the front wall 3 for rotation with the sleeve, but this bushing has no adjustment inwardly or outwardly with respect to the casing; it being held in place by a flange 15a at its inner end and a nut 15b threaded thereon, which engages opposite faces of the wall 3. At its outer end, the bushing carries a screw 16, see Figure 2, which projects within a slot 17 that is formed lengthwise of the sleeve. The inward and outward adjustment of the sleeve for normal operation of the lock is limited by the screw engaging with the ends of the slot 17, but when the screw is removed, the sleeve may be adjusted inwardly an additional distance for re-setting the lock.

Fixed to the bushing 15, is a hand, or pointer, 18, the outer end of which terminates closely to the numbered dial surface 5 so that an exact setting of the sleeve 12 and parts connected therewith may be made for releasing the lock, and a coiled spring 20 encircles the inner end of the shaft 10 and this bears against the inner end of the sleeve 12 to urge the latter outwardly. The shaft 10 has lateral lugs 25 at its outer end and has a longitudinal slot 26 cut in this end which permits the two parts of the divided end of the shaft 108

- to be sprung together to enter the outer end of the sleeve as is necessary when the sleeve is to be drawn to its outer limit for setting the lock. When the sleeve is adjusted inwardly to release the lock, these divided portions spring apart and the stops 25 engage over the end of the sleeve, as in Figure 2, to hold it against outward displacement by the pressure of the spring 20.
- 10 Fixed within the casing 1, between the end walls 2 and 3, is a collar 30 having two annular ribs 31 and 32 formed therein. These ribs have inwardly inclined, or beveled surfaces 33 facing the wall 3 and have abrupt, 15 square-cut bottom surfaces 34. A notch 36 is cut through the upper rib for the passage of a latch bolt, as will presently be described, and a block 38 is fitted beneath the bottom rib and this has an inclined surface 38a continuing from the inclined surface of the rib. This block, as presently described, is used in the re-setting operation.
- 20 A laterally directed arm 40 is fixed to the lower end of the sleeve 10 and, at its outer end, 25 it contains a continuing latching bolt 41 slidably mounted within the arm, with its outer end portion beveled and normally overlying the ribs of the collar 30. Inward and outward travel of the bolt 41 is limited by a pin 30 42 that is fixed in its inner end and which extends outwardly through a longitudinal slot 43 in the arm 40. A coiled spring 44 engages the inner end of the sleeve to urge it outwardly.
- 35 When the present lock is used for controlling an electric circuit, the mechanism, as shown in Figure 2 is employed. This view shows a circuit contact 45 of U-shape, fitted to a block 46 of insulating material and secured to the base wall of the housing by means of an insulated screw, or bolt, 48. This contact is directly in radial alignment with the slot 36 through the rib 31. One wire 49 of an electric circuit is connected to 45 the bolt 48 and another wire 50 is connected to the lock casing, so that an electrical connection between the contact 45 and the casing, as provided through the arm 40, will complete an electric circuit, which may be 50 used for various purposes and in various purposes and in various ways. As is indicated diagrammatically in Figure 2, the circuit wires lead through a source of electricity 51 to a solenoid 52, or other circuit 55 controlled device, which may be operatively connected with a mechanism 53 for actuating a latch or lock.
- 60 When the present mechanism is used with a bolt lock, mechanism as disclosed in Figure 6 is employed and this is substituted for the contact mechanism 45 of Figure 2. In Figure 6, 60 designates a slidably mounted locking bolt fixed within the casing and adapted to be moved inwardly by actuation 65 of a bell crank 62 that is operatively con-

nected therewith. A spring 63, supported by a bracket 64, bears against the bolt to move it outwardly. The bell crank has an upwardly directed arm 62a adapted to be depressed by the latch bolt at the end of the arm 40 to thereby draw the bolt 60 inwardly. The bolt 60 in this way could serve as the ordinary bolt as used in a door lock.

70 For use in re-setting the lock after it has been tampered with, there is a locking pawl 70 pivotally mounted on the inner end of the arm 40 and this has a hooked end 71 adapted to lock over the pin 42 at the inner end of the latch bolt 41 after the latter has been moved inwardly to a certain limit. The pawl, also, has an upturned, inner end 72 adapted to be engaged with the front wall of the casing to release the hook from the pin for outward movement of the bolt.

75 Assuming the device to be so constructed and set as in Figure 2, it is used as follows:

To set the parts in locked position, the operator grasps the knob 13 and draws the sleeve directly outward to its outer limit. This places the arm 40 in the position as 80 designated in dotted lines in Figure 2. The knob is then rotated so that the sleeve will swing the arm 40 and its bolt 41 to some position out of alignment with respect to the slot 36 in the rib 31. Only authorized persons are to know the exact numeral of the 85 dial to which the pointer 18 must be adjusted in order to bring the latch bolt 41 at the end of arm 40 into exact registration with the slot 36 so that, on depression of the sleeve, 90 the bolt will move downwardly through the slot and into the U-shaped contact to thereby complete the electric circuit for actuating the mechanism associated therewith. If an unauthorized person attempts to release the 95 lock and does not have the exact dial setting required, the bolt 41 will be forced inwardly by passing down the inclined surface of the rib 31 and it will finally snap beneath the 100 rib and will thereby lock so that it cannot 105 be drawn out for another trial.

110 In order to functionally re-set the parts after the lock has been tampered with in this manner, an authorized person who knows the one numeral required for the re-setting 115 operation rotates the pointer into registration with this proper numeral on the dial. This places the bolt 41 directly over the block 38. He then withdraws the screw 16 to free the sleeve for further downward movement and presses downwardly on the knob 13 so that the bolt 41 which, by this proper adjustment, has been positioned exactly above the block 38, will be moved inwardly by its sliding contact with the block 120 until the hooked end of the pawl 70 locks over the pin 42 of the bolt 41. This holds the bolt free of the ribs. The operator then 125 pulls outwardly on the knob, thereby moving the sleeve 12 outwardly and again rais- 130

ing the arm 40 to the upturned position of Figure 2 so that the inner end of the pawl is finally brought against the top, or upper surface, of the casing and the pawl is caused 5 to be released from the pin 42 and the bolt will be pushed outwardly by its spring 44 to its normal position. The screw 16 is then re-set and the lock is again ready for use. To release the lock bolt 60, as of Figure 6, 10 the arm 40 is adjusted to the proper position by reference to the pointer 18, and the sleeve is then depressed so that the arm bolt 41 is brought into contact with the bell crank arm 62a to rock the lever to withdraw 15 the bolt.

I claim:

1. In a device of the character described, a closed housing, a ring fixed within the housing and having an annular shoulder projecting from its inner surface with a slot cut therethrough, a lock operating sleeve mounted in the housing coaxially of the ring and provided with an actuating portion outside of the housing whereby it may be rotated and 25 moved inwardly or outwardly, an arm fixed to the inner end of said sleeve with a yieldable latch bolt at its end normally overlying the shoulder and adapted to snap beneath the shoulder by inward movement of the operating 30 sleeve, except at exact settings, to thereby render the device inoperative, a marked surface on the outside of the housing, an indicator movable with the operating sleeve for use in conjunction with the marked surface 35 for locating said latch bolt in registration with said shoulder slot for its passage through the latter and a lock release element alined with the slot and adapted to be functionally engaged by the latch bolt only when 40 the latter is moved thereagainst through said slot.

2. In a device of the character described, a closed housing, a ring fixed within the housing and formed about its inner surface with 45 spaced, annular shoulders, the outer shoulder of which has a slot cut therethrough, an element of a lock release mechanism fixed within the housing and within the ring in alinement with said slot, a shaft mounted in the housing coaxially of the ring, a sleeve slidably and rotatably mounted on the shaft, an arm fixed to the inner end of the sleeve, an inwardly yieldable latch bolt slidably mounted in the outer end of the arm, means at the outer 50 end of the sleeve whereby it may be rotated and moved longitudinally of the shaft, yieldable means normally urging the sleeve to its outer limit, a dial marked on the outer face of the lock, a pointer carried by the sleeve for 55 use in conjunction with the dial for positioning the latch bolt of said arm in alinement with the slot so that inward movement of the sleeve will cause said latch bolt to pass through the slot to engage functionally with 60 the lock release element; said latch bolt being 65

adapted, if not alined with the slot, to be depressed by engagement with the shoulder and to lock beneath the latter to thereby render the device inoperative.

3. A device of the character described comprising a closed housing, a ring fixed within the housing and formed about its inner surface with a plurality of spaced, annular shoulders, the outer shoulder having a slot cut therethrough, an element of a lock release mechanism fixed within the ring in alinement with said slot, a shaft mounted in the housing coaxially of the ring, a sleeve slidably and rotatably mounted on the shaft and having an actuating portion outside the housing, an arm fixed to the inner end of the sleeve, a yieldable latch bolt mounted at the end of the arm, yieldable means normally urging the sleeve to its outer limit, a dial marked on the outer face of the lock, a pointer carried by the sleeve for use in conjunction with the dial for positioning the latch bolt of said arm in alinement with the slot for passage through the latter incident to initial inward movement of the sleeve to engage functionally with the lock release element; said latch bolt being adapted, when the sleeve is moved inwardly, to be depressed by engagement with the outer shoulder if not alined with the slot therein and to lock beneath the shoulder to render the device inoperative, and a re-setting block fixed within the housing with an inclined surface by means of which said latch bolt will be depressed by a second inward movement of the sleeve, and a pawl carried by the arm for locking with the latch bolt to retain it in its depressed position for re-setting and releasable by its contact with the housing by return of the sleeve to its normal position.

Signed at Tacoma, Washington, this 19th day of April, 1929.

PETER MARKOVICH.
